(57) **CLAIM**

The ornamental design for a medical inspection instrument, as shown and described.

DESCRIPTION

FIG. 1 is a top, front, left perspective view of a medical inspection instrument, showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

In the drawings, the broken lines depict portion of the medical inspection instrument that form no part of the claimed design.

1 Claim, 7 Drawing Sheets
